UNITED STATES PATENT OFFICE.

EMANUEL WAGNER, OF NEW YORK, N. Y.

ROTARY VACUUM-FILTER.

1,198,880.

Specification of Letters Patent. Patented Sept. 19, 1916.

Application filed March 13, 1913. Serial No. 754,062.

To all whom it may concern:

Be it known that I, EMANUEL WAGNER,
a subject of the King of Hungary, and resi-
dent of the city of New York, in the county
5 of New York and State of New York, have
invented certain new and useful Improve-
ments in Rotary Vacuum-Filters, of which
the following is a specification.

The following is a specification.

10 The present invention relates to an improvement in filters specially adapted for use in connection with the cyanid process for the purpose of separating the solution from the pulp or slimes. Filters of this type have been in use heretofore and comprise usually 15 a filtering material, such as for instance cloth or a similar fabric, which travels over one or more rotating wheels in one or more tanks, in one of which is contained the pulp and the other one of which is filled with 20 water for the purpose of washing the cake formed, suitable means being provided for creating a suction or vacuum in rear of the filtering material while the same travels in the tank containing the pulp, and further- 25 more means being used for removing, for instance by air pressure, the cake after washing. Attempts have been made to treat sands containing a reasonable amount of slimes or vice versa; much trouble has been 30 experienced, however, due to the fact that the sands, if introduced either directly or indirectly into a tank containing a filter working with a submerged filtering surface, soon separate out to such an extent that a fur- 35 ther operation of the machine becomes impossible. It has been attempted to use partly submerged filters in the form of a drum, onto the filtering surface of which the pulp has been fed from above. These de- 40 vices were, however, defective for the reason that no positive means has been provided for retaining the pulp on the filtering surface, and furthermore the drum was submerged in a tank which even if it con- 45 tained clear water only at the start, soon collected such an amount of settled sands and slimes that, although elaborate agitating devices were made use of for separating and removing the settled sands, the machine be- 50 came soon useless.

One of the objects of the present invention is to provide a vacuum filter which obviates these defects in that it consists of a continuously rotating drum having a filtering medium in connection with means which retains the pulp upon the same, such pulp

being fed directly on top of the filtering medium, the usual tank being entirely done away with and the cake formed being washed, or rather the solution still contained therein being replaced by water which is contained in a shallow trough into which the filtering medium is dipped during its travel. 60

Another object of the invention is to provide a filter in the form of a rotary drum, the filtering medium of which is divided into a number of sections, any one of those sections being adapted to be replaced independently of the others. 65 70

A further object of the invention is to provide a filtering medium made of a plurality of units which communicate through compartments with a suction pump or similar device, the communication between the said pump and each filtering unit being controlled by an individual valve, which valves are actuated in the rotation of the drum by a simple operating mechanism. 75

A still further object of the invention is 80
to provide a launder for feeding the pulp
or slimes onto the filtering drum, which
launder is provided with means which
evenly distributes the sands and slimes over
the whole width of the filtering drum. 85

With these and other objects in view, which will more fully appear as the nature of the invention is better understood, the same consists in the combination, arrangement and construction of parts hereinafter 90 fully described, pointed out in the appended claims and illustrated in the accompanying drawings, it being understood that many changes may be made in the size and proportion of the several parts and details of 95 construction within the scope of the appended claims without departing from the spirit or sacrificing any of the advantages of the invention.

One of the many possible embodiments of the invention is illustrated in the accompanying drawings, in which:—

cal section taken through said launder; and Fig. 8 is a sectional detail of construction of said launder.

In the drawings, the numeral 10 indicates the drum of the filtering apparatus, such drum being made of two parts, in the form of wheels 11 and 12. Each wheel comprises a rim 13, which is made of a plurality of sections suitably bolted together at 14, 14, and forming an airtight annular compartment 15. The compartment of the wheel 11 is connected by and communicates through hollow spokes 16 with a hollow hub 17, and in a similar manner communicates the compartment of the wheel 12 through hollow spokes 18 with a hollow hub 19. The hubs 17 and 19 of the two wheels are bolted to a shaft 20 in any suitable manner. The hub 17 is made integral with, or attached to, a horizontal pipe section 21, which is connected with a suction pump or similar device, adapted to create a vacuum in the compartment of the wheel 11. In a similar manner is made the hub 19 integral with, or attached to, a pipe section 22, the latter being connected with a force pump which serves to supply pressure to the compartment of the wheel 12. The pipe sections 21 and 22 are arranged in alinement with each other and with the shaft 20, and form the journals of the drum, said journals being rotatably mounted in bearings 23, 23.

Upon the peripheral portions of the rims 13 are mounted the filtering units 24, 24. Each unit comprises a bottom 25, preferably made of wood, its upper surface having grooves 26, 26, which extend throughout the length of said bottom, and intersect two transverse comparatively deeper channels 27 in said bottom. These channels slant from the longitudinal edges of said bottom toward its center line, where apertures 28, 28 extend through the same. Each bottom 25 has stretched over its grooves 26 a filtering medium 29, such as for instance cloth or canvas, and securely fastened to the said bottom, preferably, to its underface by means of nails 30, 30, or other suitable fastening devices. The sides of the filtering units are formed by strips 31 of iron or wood, such strips being attached to the said bottoms and extending a substantial distance above their upper faces, forming thereby water-proof pans, adapted to receive a suitable amount of pulp or slimes. The filtering units so formed are placed side by side upon the wheels 11 and 12 and bolted or otherwise fastened to flanges 32, 32, formed upon the peripheral portions of said rims. The longitudinal axes of the filtering units are arranged, as clearly shown in Figs. 1 and 2 of the drawings, parallel to the longitudinal axis of the shaft 20. A gasket 33 is placed between the bottom of each filtering unit and the peripheral por-

tions of two rims. One of the apertures 28 in the bottom portion of each filtering unit registers with an opening 34 in the rim of the annular compartment of the wheel 11, each opening leading to an individual valve chamber 35, arranged within the said compartment. A rotary valve plug 36 is mounted within each valve chamber, having a passage 37 which is adapted to register with an opening 38 in its valve chamber, and to open thus a communication between the suction pump and the respective filtering unit, such communication being closed as soon as the valve plug is rotated to bring its passage out of alinement with the opening 38. The valve plugs 36 are operated automatically in the rotation of the drum by stationary pins 39 and 40, which are attached to a support 41 and project into the path of the cross-like actuating means 42, which are keyed or otherwise attached to said valve plugs. Each actuating means 42 comprises four arms 43, 43, which are arranged 90° apart, and adapted to coöperate with the pins above mentioned in such a manner that when an arm, in the rotation of the drum, is brought into contact with one of said pins, said arm will be shifted through an angular distance of 90°, thereby resulting in a turning of the valve through the same distance, and opening or closing the communication between the suction pump and respective filtering medium, as the case may be. The other aperture 28 in each bottom 25 communicates through an opening 44 in the peripheral portion of the wheel 12 with a valve chamber 45, arranged in the compartment of the wheel 12. Each valve chamber 45 is provided with a valve plug 46, which is in all respects identical with the valve plug 36 above mentioned. The valve plugs 46 carry actuating means 47, similar to the actuating means 42 of the valve plugs 36. The actuating means 47 are adapted to coöperate with pins 48 and 49, which are attached to a support 50.

The pulp is fed onto the filter by one or more distributing launders 51, each having converging sides 52 and 53, its bottom 54, which is slanting, being provided with a row of holes 55, that are arranged in a line parallel to the side 52 of the launder. The inner face of the bottom is covered with sheet iron, denoted by the numeral 56, said iron having apertures 57 in alinement with the holes 55, but of a smaller diameter. The launder is arranged above the drum 10, the material flowing through the holes of its bottom being directed by a dash-board 58 into the filtering units as the same travel in the direction of the arrow, shown in Fig. 1, past said dash-board. It will be observed that the pulp flows into the launder more or less parallel with its side 53 for the reason that the side walls of the section 51' thereof

are parallel to each other and to the wall 53, and is discharged through the holes 55 in the bottom thereof in such a manner that each hole discharges about the same amount 5 of sands and slimes over the whole length of the filter drum if the launder is given the proper inclination. This is due to the fact that the holes 55 in the bottom of the launder are arranged in a line which is inclined to 10 the direction of the flow of the pulp.

Below the filtering frame is located a shallow trough 59 containing wash-water, through which the filtering units are carried in their travel. It is obvious that, instead of the trough, spray pipes may be used. Above the trough 59 is disposed a hopper 60 in close proximity to the filtering frame, said hopper receiving the cakes removed by pressure from the filter, spray 15 pipes 61 facilitating the removal of the cakes and cleaning at the same time the filtering surfaces of the units, if required.

The operation of this device is as follows: The filter is rotated in the direction of the 25 arrow indicated in Fig. 1 of the drawings, and the pulp, that is to say the material to be filtered, flows into the launder 51. A rotary valve plug 36 is set by the pin 40 to an open position before its filtering unit arrives 30 beneath the launder; a communication is thus established between the suction pump and the said filtering unit. As the unit travels past the dash-board 58, the pulp is fed onto its filtering medium 29 and held 35 thereon, since the filtering unit is made in the form of a pan. Inasmuch as the pan is in communication with the suction pump, the solution is drawn through the filtering medium into the compartment 15 of the 40 wheel 11, and thence through the hollow spokes to the pump. If the quantity of the material fed to the filtering medium is smaller than the maximum capacity of the filter, the solid constituents, upon traveling 45 about through one-fourth of a revolution of the drum, form a moist cake, adhering to the surface of the filtering medium. This cake is then dried until it reaches the trough 59, in which it is washed, that is to say, due to 50 the suction, the rich solution in the cake is replaced by water from the trough 59. The washed cake is then carried by the drum toward the hopper 60, where the pin 39 closes 55 the communication between the unit and the suction pump, the pin 48 acting then upon the valve plug 46 of the said filtering unit, establishes a communication between the force pump or air compressor and the unit, whereby the cake is blown off into the 60 hopper 60. The spray pipes 61 aid in discharging the cake and at the same time clean the filtering surface. In the further rotation of the drum, the pin 49 actuates again the valve plug 46, shutting off thereby the pressure, after which the pin 40 again opens a

communication between the suction pump and the said filtering unit, and the cycle now described is again repeated. It is to be observed that the hopper 61 may be located directly underneath the filtering drum, in 70 which case, however, the trough 59 must be substituted by spray pipes, which are arranged in front of and above said hopper. Obviously in this case corresponding changes must be made in the location of the 75 actuating pins 39, 48 and 49.

From the foregoing it will be seen that with the apparatus herein described a mixture of sands and slimes can be handled without the aid of agitating devices which 80 are usually employed in filters working with a submerged filtering surface. The apparatus is simple, the number of parts necessary to build up the filter is reduced to the smallest possible, the construction is inexpensive, and permits of easy renewals and 85 repairs.

What I claim is:—

1. In an apparatus for recovering values from ore solutions, the combination with a 90 rotary drum having two independent compartments, of a plurality of independent and detachable filtering units fixedly attached to the periphery thereof, each unit comprising a pan having a perforated bottom and a filtering material above said bottom, said pans communicating through said perforations with said compartments, two 95 valves associated with each pan for controlling the communications between the same and said two compartments, a suction system connected with one of said compartments, a pressure system connected with the other one of said compartments, and means automatically operated in the rotation of 100 said drum for actuating said valves.

2. In an apparatus for recovering values from ore solutions, the combination with a 105 rotary drum having two independent compartments, of a plurality of independent and detachable filtering units fixedly attached to the periphery thereof, each unit comprising a pan having a perforated bottom and a filtering material above said bottom, said pans communicating through said 110 perforations with said compartments, two valves associated with each pan for controlling the communications between the same and said two compartments, a suction system connected with one of said compartments, a pressure system connected with the other one of said compartments, means automatically operated in the rotation of said 115 drum for actuating said valves, and means for feeding the substance to be filtered into 120 said pans from above during the rotation of said drum.

3. A distributing launder comprising an inclined trough having converging sides, the bottom of said trough being provided with 130

a plurality of holes in a line parallel to one side of said trough, and means for directing the flow of material into said launder in a direction substantially parallel to the other 5 side of said trough.

4. In an apparatus for recovering values from ore solutions, the combination with two rotary rings forming two independent compartments, of a plurality of independent 10 and detachable filtering units fixedly attached to the peripheries of said two rings, each unit comprising a pan having a grooved perforated bottom and a filtering material resting upon said bottom, said pans communicating each through a perforation with one of said compartments and through a perforation with the other one of said compartments, two valves associated with each 15 pan for controlling the communications between the same and said two compartments, a suction system connected with one of said compartments, a pressure system connected with the other one of said compartments, and means automatically operated in the 20 rotation of said rings for actuating said valves.

5. In an apparatus for recovering values from ore solutions, the combination with two rotary rings forming two independent compartments, of a plurality of independent 30 and detachable filtering units fixedly attached to the peripheries of said two rings, each unit comprising a pan having a grooved perforated bottom and a filtering material resting upon said bottom, said pans communicating each through a perforation with one of said compartments and through a perforation with the other one of said compartments, two valves associated with each 35 pan for controlling the communications between the same and said two compartments, a suction system connected with one of said compartments, a pressure system connected with the other one of said compartments, and means automatically operated in the 40 rotation of said rings for actuating said valves, and means for feeding the substance to be filtered into said pans from above during the rotation of said rings.

50 6. In an apparatus for recovering values from ore solutions, the combination with two rotary rings forming two independent compartments, of a plurality of independent and detachable filtering units fixedly attached to the peripheries of said two rings, each unit comprising a pan having a grooved 55 perforated bottom and a filtering material resting upon said bottom, said pans communicating each through a perforation with one of said compartments and through a 60 perforation with the other one of said compartments, two valves associated with each pan for controlling the communications between the same and said two compartments, 65 said valves being disposed in said compartments, a suction system connected with one of said compartments, a pressure system connected with the other one of said compartments, and means automatically operated in the rotation of said rings for actuating said valves, and means for feeding the substance to be filtered into said pans from above during the rotation of said rings.

ments, a suction system connected with one of said compartments, a pressure system connected with the other one of said compartments, and means automatically operated in the rotation of said rings for actuating said valves. 70

7. In an apparatus for recovering values from ore solutions, the combination with two rotary rings forming two independent compartments, of a plurality of independent 75 and detachable filtering units fixedly attached to the peripheries of said two rings, each unit comprising a pan having a grooved perforated bottom and a filtering material resting upon said bottom, said pans communicating each through a perforation with one of said compartments and through a perforation with the other one of said compartments, two valves associated with each 80 pan for controlling the communications between the same and said two compartments, said valves being disposed in said compartments, a suction system connected with one of said compartments, a pressure system connected with the other one of said compartments, means automatically operated in the rotation of said rings for actuating said valves, and means for feeding the substance to be filtered into said pans from above during the rotation of said rings. 95

8. In an apparatus for recovering values from ore solutions, the combination with two rotary rings forming two independent compartments, of a plurality of independent 100 and detachable filtering units fixedly attached to the peripheries of said two rings, each unit comprising a pan having a grooved perforated bottom and a filtering material resting upon said bottom, said pans communicating each through a perforation with one of said compartments and through a perforation with the other one of said compartments, two valves associated with each 105 pan for controlling the communications between the same and said two compartments, a hollow shaft having two non-communicating sections, one of which is connected with a suction system and the other one with a pressure system, and hollow spokes connecting one section of said shaft with one of 110 said compartments and the other section of said shaft with the other one of said compartments. 115

9. In an apparatus for recovering values from ore solutions, the combination with two rotary rings forming two independent compartments, of a plurality of independent 120 and detachable filtering units fixedly attached to the peripheries of said two rings, each unit comprising a pan having a grooved perforated bottom and a filtering material resting upon said bottom, said pans communicating each through a perforation with one of said compartments and through a 125 perforation with the other one of said compartments, two valves associated with each pan for controlling the communications between the same and said two compartments, 130 said valves being disposed in said compartments.

parts, two valves associated with each pan for controlling the communications between the same and said two compartments, a hollow shaft having two non-communicating sections, one of which is connected with a suction system and the other one with a pressure system, and hollow spokes connecting one section of said shaft with one of said compartments and the other section of said shaft with the other one of said compartments, the number of said spokes being independent of the number of the filtering units.

Signed at New York, in the county of New York and State of New York, this 21st ¹⁵ day of February, A. D. 1913.

EMANUEL WAGNER.
